UNITED STATES PATENT OFFICE

132,610

DESIGN FOR A WATER FAUCET FILTER

Isidore Zuckermann, New York, N. Y.

Application October 7, 1941, Serial No. 103,671

Term of patent 14 years

To all whom it may concern:

Be it known that I, Isidore Zuckermann, a citizen of the United States of America, residing at New York city, county of New York, and State of New York, have invented a new, original, and ornamental Design for a Water Faucet Filter, of which the following is a specification, reference being had to the accompanying drawing forming a part thereof, wherein:

Figure 1 is a top plan view of a water faucet filter, showing my new design;

Figure 2 is a view in side elevation, and
Figure 3 is a bottom plan view thereof.

I claim:

The ornamental design for a water faucet filter, as shown.

ISADORE ZUCKERMANN.
